(57) CLAIM

The ornamental design for a golf club grip with contrasting underlayment, as shown and described.

DESCRIPTION

FIG. 1 is a perspective view of the invention.

FIG. 2 is a side view of the invention.

FIG. 3 is another side view of the invention.

FIG. 4 is another side view of the invention.

FIG. 5 is another side view of the invention.

FIG. 6 is a bottom view of the invention; and,

FIG. 7 is a top view of the invention.
